Primary Examiner — Kevin K Rudzinski*Assistant Examiner* — Richard Kearney(74) *Attorney, Agent, or Firm* — Cionca IP Law P.C.; Marin Cionca(57) **CLAIM**

The ornamental design for a trellis clip, as shown and described.

DESCRIPTION

1. Trellis clip

1.1 : Perspective

1.2 : Right

1.3 : Left

1.4 : Back

1.5 : Front

1.6 : Top

1.7 : Bottom

The trellis clip in which the claimed design is embodied may be used in a trellis structure for additional support of plants.

1 Claim, 7 Drawing Sheets(56)
